UNITED STATES PATENT OFFICE.

MARK S. GRAVES, OF NORTH YAKIMA, WASHINGTON.

SWITCH-FROG.

1,239,001.

Specification of Letters Patent.

Patented Sept. 4, 1917.

Application filed April 15, 1916. Serial No. 91,419.

To all whom it may concern:

Be it known that I, MARK S. GRAVES, a citizen of the United States, residing at North Yakima, in the county of Yakima and 5 State of Washington, have invented certain new and useful Improvements in Switch-Frogs, of which the following is a specification.

My invention relates to new and useful 10 improvements in switch frogs and more particularly to an automatic frog.

The primary object of the invention is the provision of a frog so constructed as to prevent pounding and to provide a continuous 15 surface for the wheels of the rolling stock.

A further object of the invention is the provision of an automatic switch frog provided with swinging or pivoted blocks 20 adapted to be operated by the flange of the wheel of the rolling stock.

Another object of the invention is the construction of a frog in such a manner as to prevent the accumulation of snow or other 25 foreign substances which might interfere with the operation of the same.

With these and other objects in view the invention consists in the novel details of construction and arrangement of parts 30 which will be more clearly understood from the following description and drawings, in which,

Figure 1 is a top plan view of the frog, showing one covering plate removed, and

35 Fig. 2 is a side view of the frog, parts being broken away.

My frog is equally well adapted for use with street or steam railways and in the drawings, the numeral 1 indicates ties or other suitable supports for the tracks. My 40 improvements comprise a base plate indicated at 2 which is adapted to be secured to the ties in any suitable manner and said plate 2 is provided with openings provided 45 to receive the spikes 3 or other fastening means for securing the track 4 in position. A frog point is indicated at 5 and may be secured to the plate 2 in any suitable manner. The ends of the track 4 are cut away 50 from the tread portion to a point substantially midway of the webs, thereby forming an extension 6 and blocks 7 are pivotally connected to the ends of the rails 4 as is clearly shown by means of the bolts 8 55 which pass through extensions 9 formed on the blocks 7 and through the tracks 4

and plate 2. The opposite ends of the block 7 are curved as shown at 10 and the purpose of which will be presently described. The curved ends of the blocks 60 engage the end of the switch point 5, as is more clearly shown in Fig. 1 of the drawings.

Castings 11 are formed on the plate 2 or may be secured thereto in any suitable manner and the inner face of the castings are cut away, as indicated at 12, so as to receive the pivoted blocks 7 when swung inwardly. Springs 13 are secured to the casting in any well known manner and are adapted to engage 70 the face of the pivoted block 7. The springs normally tend to force the pivoted block into engagement with the end of the frog point 5.

A covering plate 14 is adapted to be secured to each casting by means of bolts 15 or other suitable fastening means and the covering plate excludes dirt or other foreign substances from the working parts of the frog.

Having fully described the details of construction it is thought that the operation and advantages of my frog will be clearly understood. Considerable difficulty has been experienced in the past in that the rolling stock while passing over the frogs would cause a pounding thereby damaging the frog as well as the wheels of the rolling stock. It is the object of my invention to overcome this pounding and to form a continuous surface over which the wheels will pass. While passing over the frog, the tread portion of the wheels will hold one of the blocks 7 stationary and the flange of the wheel will force the other block 7 into the space 12 formed in the casting 11. The blocks 7 being forced 95 inwardly will put the spring 13 under tension and when the flange of the wheel passes over the frog, the block will assume its original position by the pressure of the spring 100 thereon. By providing the curved ends of the blocks 7, it will be seen that the blocks will be operated by the wheels, while the rolling stock is passing in either direction. It will be further seen that I have provided 105 a switch frog which may be easily attached to any track and if parts should become broken they can be easily replaced.

Having thus fully described my invention what I claim as new and desire to secure by 110 Letters Patent is:

1. A switch frog comprising a base, rails

secured to the base, blocks pivotally connected to the tracks, castings secured to the base and provided with cutout portions to receive the blocks, and springs secured to the castings and engaging the pivoted blocks.

2. A switch frog comprising a base plate, rails secured to the base, blocks pivotally connected to the rails, castings secured to the base, springs secured to the castings and engaging the pivoted blocks, and plates secured to the castings.

3. A switch frog comprising a base plate, rails secured to the base, blocks pivotally connected to the rails, castings secured to the base and provided with cutout portions, springs secured to the castings and adapted to engage the pivoted blocks, and covering plates secured to the castings.

4. A switch frog including a base, housings mounted on said base, rails secured to the base, and blocks movably connected to said rails and positioned in said housings.

5. A switch frog including a base, housings mounted on said base, rails engaging one end of said housings, springs placed in said housings, and blocks received in said housings and engaged by said springs.

6. A switch frog, including a base, housings mounted on said base, blocks movably positioned in said housings, and resilient members secured to said housings and normally causing said block to protrude from the latter, and rails connected to said blocks.

7. A switch frog including a base, housings mounted on said base, and provided with removable covers, and blocks movably mounted in said housings.

In testimony whereof I affix my signature in presence of two witnesses.

MARK S. GRAVES.
